FIG. 5.

Patented July 19, 1927.

1,636,169

UNITED STATES PATENT OFFICE.

CHARLES H. CHALMERS, OF MINNEAPOLIS, MINNESOTA.

LIQUID-FUEL HEATING APPARATUS.

Application filed August 4, 1922. Serial No. 579,671.

This invention relates to such liquid fuel heating apparatus generally but is more particularly adapted for use in connection with furnaces such as are commonly employed in connection with steam or water boilers or air drums for heating homes and other buildings. The construction of this apparatus and the arrangement of its parts are such that it may readily be employed 5 in conjunction with the usual coal-burning furnace, the necessary changes to convert such a furnace into a liquid fuel burning furnace being practically minimized. Likewise, any desired re-conversion to coal fuel 10 is easily and readily accomplished. Broadly, it may be noted that the liquid fuel burner is substantially a unitary structure which may be introduced within the fire-box of any of the common type of coal-burning furnaces. The liquid fuel is fed 15 to the burner by a pump while air under pressure is supplied to the burner to atomize the fuel. Means are provided automatically to control the apparatus both in response 20 to failure of ignition at the proper time and in response to thermal changes in the building to be heated.

The object therefore of the invention is to provide an improved liquid fuel heating 25 apparatus.

Other objects of the invention will more fully appear from the following description and the accompanying drawings and will be pointed out in annexed claims.

In the accompanying drawings there has been disclosed a structure designed to carry out the objects of the invention, but it is to be understood that the invention is not confined to the exact features shown, as 35 various changes may be made within the scope of the claims which follow:

In the drawings:

Figure 1 is a plan view of the apparatus and indicating its operative relation to a 40 furnace shown in horizontal section adjacent the fire-box and ash-pit;

Figure 2 is a view in side elevation of the blower and the burner in operative position, the burner and furnace being shown 45 in vertical section;

Figure 3 is an enlarged detailed vertical sectional view showing the mode of demountable attachment of one of the flaring side members of the burner and taken on 50 the line 3-3 of Figure 1;

Figure 4 is a vertical sectional view on

the line 4-4 of Figure 1 to show the oil pump mechanism;

Figure 5 is an enlarged view in vertical section on the line 5-5 of Figure 1;

Figure 6 is an enlarged view in vertical section on the line 6-6 of Figure 1.

In the selected embodiment of the invention here shown the liquid fuel, such as one of the common distilled fuel oils, is supplied 55 to the burner nozzle under a relatively light pressure. The nozzle is preferably upwardly directed and air is jetted upwardly adjacent the nozzle to spray the oil upwardly toward a superposed target. The 60 nozzle, air port, target and associated parts are all positioned within a fire-box and carried by a single leg supported upon the floor of the ash-pit. The blower, its motor, the pressure chamber and associated parts 65 are all carried by a two-legged base supported upon the floor of the building. By this means, the advantageous three-point mounting is obtained.

In describing the construction of the apparatus, reference may first be had to the 70 burner and its parts.

The air supply pipe 11 extends from a coupling 12 bolted to the base 13 having two supporting legs 14 adapted to be positioned upon the floor 15 of the building adjacent the furnace. This air supply pipe 11 extends within the lower part of the furnace, the usual hinged door having first 75 been removed and a modified form of demountable door having been substituted as hereinafter described. This pipe is positioned so that its end terminates in the fire-box 16 short of the vertical axis of the furnace and is provided with a collar 17 supported by a leg 18 resting upon the bottom of the ash-pit floor. An elbow 19 is secured 80 to one end of the air pipe 11 and upwardly terminates so that its axis preferably coincides with the vertical axis of the fire-box. The fuel oil pipe 21 may advantageously 85 extend within the air pipe 13. Its nozzle end has an elbow 22 upwardly terminating and carrying a short pipe section 23 which is held in spaced position by means of set 90 screws 24 received in threaded engagement through the air elbow 19. Three such set screws are preferably employed. The nozzle 25 is fitted over the upper end of the pipe section 23 and rests upon the set screws. The inner annular end portion of the nozzle 95 is outwardly inclined or flared to assist

in the spread or spraying of the liquid fuel by the air forced upwardly past the concentric nozzle. A drip-pan 26, preferably of cast metal, is supported by the elbow 19. This pan 26 has a central aperture having an annular flange of thickened metal within which the elbow 19 projects and terminates.

A peripheral upstanding flange 27 is also 10 provided upon the casting forming the drip pan. This flange functions to collect any liquid which may escape from the nozzle without ignition. This pan has an overflow aperture to receive the upper open end of a 15 pipe section 28 joined to the elbow 29 which in turn is joined to the overflow pipe 31 which is adapted to carry the unconsumed oil to an automatic control device adapted to cut off the supply to the nozzle as here- 20 after described.

A target 32 is positioned above the nozzle in the fire-box of the furnace and is supported by the drip pan structure. The target, preferably of refractory material is 25 circular in form and provided on its under face with an annular flange presenting a depending lip 33 adapted to be seated upon a correspondingly curved recess in the upper end of each of a plurality of posts 34 mounted 30 at their lower ends upon the drip pan 26. Preferably three such posts of suitably refractory material are employed. The lower end of each post is provided with a terminally reduced portion 35 demountably 35 receivable in a socket 36 in the flanged portion of the drip-pan casting as is indicated in Figure 2. Means outwardly and upwardly flaring beyond the drip-pan are advantageously provided in order to catch 40 liquid oil which may spatter from the target or be outwardly sprayed and not ignited. Such means is here shown as a plurality of wings 37 of sheet metal shaped into the form shown in Figures 1, 2, and 3. A convenient 45 mode of demountably attaching these wings is indicated in the last named figure wherein there are shown a pair of metal clips 38 having flat portions secured to the outer face of the wing and presenting depending 50 spaced portions 39 to receive therebetween the upper edge of the drip-pan flange 27. These clips are secured to the wing by the rivet 41 which also holds the angled strip 55 presenting an upstanding finger-piece 42 whereby the wings may conveniently be positioned and removed.

A convenient means of igniting the sprayed oil is provided by the gas pipe 43 60 connected through a common form of Bunsen mixing valve 44 with the gas supply pipe 45 connected to any suitable source of gas such as the usual city mains. The end of the pipe 43 is, of course, open and terminates adjacent the bottom of the drip-pan

and during the use of this heating apparatus is normally left lighted to have the usual functions of a pilot light. The gas pipe 43 may be held to the air pipe 11 by means of the bolted clips 46.

The usual hinged door leading to the ash-pit of the furnace is preferably removed and a novel closure substituted. Such closure consists of a plate 47 of sheet metal backed by a sheet of thermally insulating material 48 such as asbestos. The plate 47 and its backing are of a dimension to abut against the walls of the furnace adjacent the ash-pit opening. A rear plate 49, also of sheet metal and of a dimension closely approximating the door opening is placed against the material 48 and this three part closure is joined into a unitary structure by the rivets 51. As is shown by the full and dotted lines in Figure 6, the closure is formed with an elongated slot 52 opening from the lower edge of the closure. Thus, the closure may be dropped into position around the pipes after installation of the latter within the furnace in operative position. A suitable means of holding the closure in reinforced closing position is provided by the spider shown in Figure 6 which is of metal cast to provide a U-shaped central portion 53 having integral radial arms 54, and a web 55. After the closure is dropped into proper position, the spider is upwardly moved into the position shown so that the U-shaped portion extends partly around the pipes, the arms abut against the outer plate and the web substantially closes the slot. The closure and spider are pressed toward the furnace wall and the set screw 56, carried by the spider, is turned to engage the periphery of the air pipe and the parts are locked in working position and yet may be readily demounted, removed, and the usual furnace door again mounted upon its hinges.

As heretofore stated this novel apparatus is adapted for use with any of the present common types of heating furnaces and, for purpose of explanation of this invention, there has been shown only a portion of the common type of such furnace. The position of the usual furnace grate 57 is shown in the dotted lines in Figure 2. However, upon installing this apparatus, such grate is removed so that the usual fire-box and ash-pit are made into one chamber.

A standard form of blower, having the housing 58, is shown as mounted upon the base 13. A convenient means of operation of the blower is shown as an ordinary type of electric motor 59 which is preferably 125 directly connected to the blower and is mounted upon the same base 13 by means of a pedestal 61 and the cable 62, leading from the motor, is adapted to be connected to a suitable source of electrical energy. The oil- 130

pipe 21 which is preferably concentrically disposed within the supply pipe 11, rearwardly extends and projects through the housing 58 of the blower at the boss 63. The 5 pipe section 64, is connected to the coupling 12 of the air pipe and to the blower housing. This pipe section 64 is provided with a valve 65 of the gate type. As shown in the enlarged detail, Figure 5, the usual gate- 10 plate 66 thereof is provided with an elongated aperture 67 to permit movement of the plate 66 about the oil-pipe 21. This valve may be adjustably set to permit the passage of the desired amount of air and 15 may be held in such adjusted position by means of a set screw 68.

The mechanism for supplying the fuel oil to the burner and its control may next be described. There is preferably employed an 20 oil tank 71 which may be sunk in the ground below the floor level as is suggested in Figure 4. This tank has a sleeve 72 at its upper open end and a man-hole cover 73 closes the opening. Preferably the cover 73 has 25 an annular upstanding wall 74 which is closed by a flanged plug 75 in turn provided with an apertured boss 70 through which extends the pipe 76. The pipe 76 is held in fixed position by means of the set screws 77. The pipe 76 downwardly extends to a point adjacent the lower end of the tank where it is connected to the housing 78 containing a suitable pump of any of the well-known 30 types. The lower portion of the pump housing 78 is provided with a supporting leg 79 to rest upon the base of the tank and is also provided with an oil intake 81 leading from a common form of screened oil inlet 82. The pump is adapted to force the oil upwardly 35 from the tank through the upright pipe 76 to the T-coupling 83, where the oil is delivered through the pipe 84.

The pump is actuated by the drive-shaft 40 vertically extending within the pipe 76 and beyond the T-coupling 83 and the coupled pipe section 86. Bearings for the drive shaft may be provided adjacent its lower end in the pump housing. The upper 45 end of the pipe section 86 is received in threaded engagement within the cored end of the bracket 87. This bracket supports the relatively small electric motor 88 which drives the shaft 85 through a coupling 80, shaft 90 and a worm 89 fast on the worm shaft 90 and meshing with the worm gear 91 pinned to the drive-shaft 85. Bearings 92 are provided by the bracket for the upper 50 end portion of the drive-shaft and are lubricated from the grease-cup 93.

The fuel oil is not pumped directly to the burner nozzle but is pumped to an elevated chamber where the oil supplied to the burner may be cut off automatically upon failure 55 of ignition or upon failure of the air sup-

ply. In other words, the failure of the air supply will automatically prevent the supply of fuel oil to the burner and, even if the air supply is functioning properly and the ignition fails, then the fuel supply will be 60 cut off from the burner.

The oil supplied to the burner nozzle is sprayed against the target beyond the nozzle by the surrounding air blast from the blower through the air pipe. The sprayed oil 65 spatters down from the target and is caught by the drip-pan 126 and by the auxiliary shields which in turn direct the sprayed oil to the drip-pan. The end of the gas pipe 43 is bent into such position that its flame 70 is directed downwardly against the drip-pan and spreads outwardly upon the upper surface thereof. As the drip from the target collects in the bottom of the pan, it comes 75 in contact with this gas flame or pilot light, and the oil is ignited first in the pan. As the oil in the pan burns it ignites the spray and in a short time the oil in the pan is all 80 consumed and the space between the three target-supporting posts or uprights becomes 85 a mass of flame which spreads around the edges of the target upwardly and outwardly. In practical operation after the ignition phenomena, the lower point of the flame is 90 approximately within one-half inch or so of 95 the nozzle.

Having thus described my invention, what I claim as new and desire to secure by Letters Patent is:

1. In a liquid fuel heating apparatus, the 100 combination of a fuel-spraying nozzle adapted upwardly to spray liquid fuel, a drip-pan surrounding said nozzle, a target adapted to be supported above said spray nozzle whereby the fuel may be sprayed upwardly thereagainst, a demountable auxiliary drip-collecting means extending upwardly and outwardly beyond the periphery of the drip-pan, and means demountably to secure 105 said auxiliary means to the drip-pan.

2. In a liquid fuel heating apparatus, the 110 combination of a fuel-spraying nozzle adapted upwardly to spray liquid fuel, a drip-pan surrounding said nozzle, a plurality 115 of supports demountably carried in spaced relation by the drip-pan and upwardly projecting therefrom, a target supported on the upper end of said supports and extending over the nozzle, and auxiliary drip-collecting members demountably carried by the drip-pan between pairs of said supports.

3. In a liquid fuel burning mechanism, a 120 vertical spraying nozzle, a refractory target, a drip-pan, detachable flares on said pan 125 said flares arranged to direct unignited fuel into said drip-pan.

In witness whereof, I have hereunto set my hand this second day of August 1922.

CHARLES H. CHALMERS.
